UNITED STATES PATENT OFFICE

101,686

DESIGN FOR A BRASSIÈRE

Zelta M. Andrus, Los Angeles, Calif., assignor to Western Corset Company, Inc., Los Angeles,
Calif., a corporation of California

Application June 20, 1936, Serial No. 63,411

Term of patent 3½ years

To whom it may concern:

Be it known that I, Zelta M. Andrus, a citizen of the United States, residing at Los Angeles, in the county of Los Angeles and State of California, have invented a new, original, and ornamental Design for a Brassière, of which the following is a specification, reference being had to the accompanying drawing forming part thereof.

The figure is a plan view of a brassière showing my new design.

I claim:

The ornamental design for a brassière, as shown.

ZELTA M. ANDRUS.
